UNITED STATES PATENT OFFICE

WALTER W. SLACK, OF SPRINGFIELD, VERMONT, ASSIGNOR TO FITZ-EMPIRE DOUBLE PIVOT LAST COMPANY, OF AUBURN, MAINE, A CORPORATION OF MAINE

LAST LATHE

Application filed October 29, 1927. Serial No. 229,736.

This invention relates to copying lathes and is disclosed as embodied in a lathe for cutting lasts. Such lathes comprise a swing frame in which a model and a last block are 5 rotated against a model wheel and cutter mounted in the machine. The model acts as a spacer between the model wheel and the swing frame, pushing out the frame when its high points come in contact with the model 10 wheel, and letting it fall back at the low points, thus regulating the depth of cut in the block. The ordinary swing frame is heavy and possessed of considerable inertia. As the leading side of the cone, for example, 15 of a last model rolls over the model wheel the swing frame is forced sharply outward and its inertia tends to keep it moving after the tip of the cone is reached, carrying the model out of contact with the model wheel. This causes the cutter to cut too high just 20 beyond the high point and leaves a bulge on the work. The model then falls violently back on the wheel, and the inertia of the swing frame causes it to twist, allowing the block 25 to fall too far toward the cutter, which then cuts too deep into the block. Conversely as the model wheel rolls into a hollow on the model there is a tendency to jar at the bottom, where the direction of relative movement between the wheel center and the model 30 center changes.

It is an object of the present invention to provide a machine in which the model shall be held steadily and firmly in contact with 35 the model wheel, by virtue of an increased or additional restoring force applied to the swing frame as it is pushed out by the model wheel, thus overcoming the tendency of the model to leave the model wheel, and vice 40 versa.

In accordance with the present invention I have provided a flexible tension member for 45 applying the additional restoring force to the swing frame, and a movable abutment over which it runs. Preferably the movable abutment is moved by a connection to the swing frame so as to increase the restoring force 50 as the swing frame moves outwardly, thus holding the model against the model wheel as

the wheel rolls up and over a high point of the model.

In the drawings

Fig. 1 is a side elevation of those parts of a last lathe necessary to an understanding of the present invention, showing the swing frame on center, that is, with the axis of the model on the face of the model wheel; 55

Fig. 2 is a similar view showing the swing frame at the outermost point of its swing; 60 and

Fig. 3 is a more extensive view showing the swing frame in its inoperative latched-out position.

The swing frame 10 is pivoted at 12 and has the well-known link 14 at each end pivoted to a crank 16 on the ordinary rocker shaft 18. The frame is pulled toward the "zero" position shown in Fig. 1 in which the axis 19 of the model is on the face 21 of the model wheel 65 by a cord 20 operated by a weight 22, and connected to the bottom of the swing frame at 24. The cord 20 passes over a fixed pulley 26, and also over a pulley 28 on a stub shaft 30 mounted in one of several holes 32 70 in one arm of a bell crank 34 pivoted at 36 on the machine frame. A link 38, adjustable in length, connects the other arm of the bell crank to the bottom of the swing frame. 75

Regarding for the moment the pulley 28 as 80 fixed it is obvious that as the swing frame is forced out from the Fig. 1 position to that of Fig. 2, the cord 20 will lift the weight 22 and the tension in the cord will be proportional to the acceleration necessary to lift the weight. 85 The upward movement of the weight is determined by the shape of the model, as is also the downward movement if the model rotates very slowly. Now the maximum acceleration of the weight occurs very close to the 90 bottom of a depression out of which the model wheel is rolling, and the acceleration becomes negative, zero or very small considerably before the top of the "hill" is reached. Therefore the cord will slacken at the top of the hill 95 and the swing frame, out of control, will bound away from the model wheel, causing the faulty cutting described above.

Consider now the situation as shown in the drawing. As the swing frame moves out 100

from the Fig. 1 position, the link 38 will tip the bell crank 34 counter-clockwise, thus raising the weight 22 faster than it would ordinarily rise. Thus additional acceleration is imparted to the weight, and the force necessary to produce it is transmitted through the cord to the swing frame, thereby providing the additional pull necessary to hold the model against the model wheel steadily as the wheel rolls over the high point of the model. The effect is reversed as the model wheel rolls down into a hollow on the model, the force diminishing until the bottom is reached. The time-cycle of this operation of course is the same as that of the swing frame movement.

The effect produced may be regulated by moving the stub shaft 30 from one to another of the holes 32, and by changing the length of the link 38 which controls the range of rotation of the bell crank 34, since the cycle of the effect produced depends on the orientation of the bell crank.

While I have herein shown the cord 20 as tensioned by the weight 22, I regard it as within the scope of my invention to use a spring or other means for this purpose, or to use an elastic cord.

Having thus described my invention, what I claim as new and desire to secure by Letters

30 Patent of the United States is:

1. In a copying lathe, a swing frame, a flexible tension member having one end fastened to the swing frame and arranged to pull the swing frame toward zero position, a movable abutment over which the tension member hangs, and means for altering the effective position of the abutment to vary the restoring force on the swing frame during each swing of the frame.

40 2. In a copying lathe, a swing frame, a flexible tension member having one end fastened to the swing frame, and a weight on its other end, arranged to pull the swing frame toward zero position, a movable abutment over which the tension member hangs, and means for altering the effective position of the abutment to vary the restoring force on the swing frame during each swing of the frame.

50 3. In a copying lathe, a swing frame, a flexible tension member having one end fastened to the swing frame and arranged to pull the swing frame toward zero position, a movable abutment over which the tension member hangs, and means for altering the effective position of the abutment as the swing frame moves in a cycle having the same period as that of the swing frame movement.

60 4. In a copying lathe, a swing frame, a flexible tension member having one end fastened to the swing frame, and a weight on its other end, arranged to pull the swing frame toward zero position, a movable abutment over which the tension member hangs, and

and means for moving the abutment as the swing frame moves.

5. In a copying lathe, a swing frame, a flexible tension member having one end fastened to the swing frame, means for creating tension in the tension member arranged to pull the swing frame toward zero position, a movable abutment over which the tension member hangs, and means connecting the abutment to the swing frame for moving the abutment as the swing frame moves.

6. In a copying lathe, a swing frame, a flexible tension member having one end fastened to the swing frame, and a weight on its other end, arranged to pull the swing frame toward zero position, a movable abutment over which the tension member hangs, and means connecting the abutment to the swing frame for moving the abutment as the swing frame moves.

7. In a copying lathe, a swing frame, a flexible tension member having one end fastened to the swing frame, and a weight on its other end, arranged to pull the swing frame toward zero position, a movable abutment over which the tension member hangs, and means for moving the abutment in the direction opposite to the movement of the swing frame, as the swing frame moves.

8. In a copying lathe, a swing frame, a flexible tension member having one end fastened to the swing frame and arranged to pull the swing frame toward zero position, a movable abutment over which the tension member hangs, and means connecting the abutment to the swing frame for moving the abutment in the direction opposite to the movement of the swing frame, as the swing frame moves.

9. In a copying lathe, a swing frame, a flexible tension member having one end fastened to the swing frame, and a weight on its other end, arranged to pull the swing frame toward zero position, a movable abutment over which the tension member hangs, and means connecting the abutment to the swing frame for moving the abutment in the direction opposite to the movement of the swing frame, as the swing frame moves.

10. In a copying lathe, a swing frame, a flexible tension member having one end fastened to the swing frame, and a weight on its other end arranged to pull the swing frame toward zero position, a movable abutment over which the tension member hangs, and means connecting the abutment to the swing frame for moving the abutment continuously in the direction opposite to the movement of the swing frame, as the swing frame moves.

11. In a copying lathe, a swing frame, a flexible tension member having one end fastened to the swing frame, and a weight on its other end arranged to pull the swing frame toward zero position, a movable abutment over which the tension member hangs, and

means for moving the abutment away from the swing frame as the swing frame rotates a high point of a model therein over the model wheel, to increase the restoring force tending to bring the swing frame to its zero position.

12. In a copying lathe, a swing frame, a flexible tension member having one end fastened to the swing frame and a weight on its other end arranged to pull the swing frame toward zero position, a lever, a pulley mounted on the lever to move therewith, over which the tension member hangs, and means for moving the lever as the swing frame moves.

13. In a copying lathe, a swing frame, a flexible tension member having one end fastened to the swing frame and a weight on its other end arranged to pull the swing frame toward zero position, a lever, a pulley mounted on the lever to move therewith, over which the tension member hangs, and means connecting the lever to the swing frame for moving the lever as the swing frame moves.

14. In a copying lathe, a swing frame, a flexible tension member having one end fastened to the swing frame and a weight on its other end arranged to pull the swing frame toward zero position, a bell crank, a pulley mounted on one arm of the bell crank over which the tension member hangs, and a link connecting the other arm of the bell crank to the swing frame.

15. In a copying lathe, a swing frame, a flexible tension member having one end fastened to the swing frame and a weight on its other end arranged to pull the swing frame toward zero position, a bell crank, a pulley adjustably mounted on one arm of the bell crank over which the tension member hangs, and a link connecting the other arm of the bell crank to the swing frame.

16. In a copying lathe, a swing frame, a flexible tension member having one end fastened to the swing frame and arranged to pull the swing frame toward zero position, a bell crank, a pulley adjustably mounted on one arm of the bell crank over which the tension member hangs, and a link adjustable in length connecting the other arm of the bell crank to the swing frame.

17. In a copying lathe, a swing frame, a flexible tension member having one end fastened to the swing frame, and a weight on its other end, arranged to pull the swing frame toward zero position, a bell crank, a pulley adjustably mounted on one arm of the bell crank over which the tension member hangs, and a link adjustable in length connecting the other arm of the bell crank to the swing frame.

In testimony whereof I have signed my name to this specification.

WALTER W. SLACK.
